ATTORNEYS

UNITED STATES PATENT OFFICE.

CHARLES J. SEITER, OF NEW YORK, N. Y.

DESIGN FOR A PLATE.

SPECIFICATION forming part of Design No. 33,627, dated December 4, 1900.

Application filed October 30, 1900. Serial No. 34,952. Term of patent 7 years.

To all whom it may concern:

Be it known that I, CHARLES J. SEITER, a citizen of the United States, and a resident of the city of New York, borough of Manhattan, in the county and State of New York, have invented and produced a new and original Design for a Plate, of which the following is a specification, reference being had to the accompanying drawings, forming a part there-
of, in which—

Figure 1 is a plan view of a plate embodying the features of my design, and Fig. 2 is a transverse section through the plate.

The leading features of the design consist of the representation of a group of rabbits upon the foreground of a landscape, on which foreground vegetables appear associated with the animals.

The minor features of the design consist in the character of the landscape and in the representation of the vegetables, some of which are in fragments, the vegetables being of the cabbage, lettuce, radish, and turnip type.

Having thus described my invention, I claim as new and desire to secure by Letters Patent—

The design for a plate herein shown and described.

In testimony whereof I have signed my name to this specification in the presence of two subscribing witnesses.

CHARLES J. SEITER.

Witnesses:

OWEN WARD,
W. C. BENJAMIN.
